(57) **CLAIM**

The ornamental design for a vertically-oriented digital camera body with top-centered shutter button, as shown and described.

DESCRIPTION

The present application is related to the following commonly-owned applications: (1) Application Ser. No. 29/126, 740, filed concurrently, and titled, Vertically-Oriented Digital Camera Body with Lens Assembly Reveal; (2) Application Ser. No. 29/126,738, filed concurrently, and titled, Vertically-Oriented Digital Camera Body with Connector Interface; and (3) Application Ser. No. 29/126,737, filed concurrently, and titled, Digital Camera Viewfinder with Graphic Display. The disclosures of the foregoing are hereby incorporated by reference.

FIG. 1 is a top, left and front perspective view of a vertically-oriented digital camera body with top-centered shutter button, the broken lines are shown to illustrate environment only and form no part of the claimed design;

FIG. 2 is a top, right, and front perspective view thereof;

FIG. 3 is a front end view thereof;

FIG. 4 is a rear end view thereof;

FIG. 5 is a bottom, left, and front perspective view thereof; and,

FIG. 6 is a top, left, and front perspective view showing a first modified form of our new design, the sole difference being minor lateral displacement of the shutter button to one side (or the other) of the camera body.
